MOLD FOR FROZEN CONFECTIONS

Walter F. Morrison, 15838 Harvest Moon Drive,
La Puente, Calif.

Filed Sept. 8, 1959, Ser. No. 57,464

Term of patent 3½ years

(Cl. D44—1)

FIG. 1.

FIG. 2.

FIG. 3.

Figure 1 is a perspective view of a mold for frozen confections showing my new design with one of the integrally formed handle, cover, and stem units shown removed from the one-piece gang mold unit;

Fig. 2 is a view in side elevation of the same; and
Fig. 3 is a view in end elevation of the same.

I claim:

The ornamental design for a mold for frozen confections, as shown and described.
